DESIGN FOR A GARTER

Floyd A. Knoll, Buffalo, N. Y., assignor to Condor Products, Inc., Buffalo, N. Y.

Application June 26, 1934, Serial No. 52,342

Term of patent 14 years

To all whom it may concern:

Be it known that I, Floyd A. KNOLL, a citizen of the United States, residing at Buffalo, Erie County, State of New York, have invented a new, original, and ornamental Design for a Garter, of which the following is a specification, reference being had to the accompanying drawing, forming a part thereof.

In said drawing:

Fig. 1 is a front perspective view of a garter as in use showing my design.

Fig. 2 is a similar view with some of the parts of the garter in different positions.

I claim:

The ornamental design for a garter as shown.

FLOYD A. KNOLL.
